(57) **CLAIM**

The ornamental design for a swivel knife holder assembly for a multi-ply reciprocating cutter as shown and described.

DESCRIPTION

FIG. 1 is a back, right side, perspective view of a swivel knife holder assembly for a multi-ply reciprocating cutter. FIG. 2 is a left side, plan view of the swivel knife holder assembly for a multi-ply reciprocating cutter.

FIG. 3 is a right side, plan view of the swivel knife holder assembly for a multi-ply reciprocating cutter.

FIG. 4 is a back side, plan view of the swivel knife holder assembly for a multi-ply reciprocating cutter.

FIG. 5 is a front side, plan view of the swivel knife holder assembly for a multi-ply reciprocating cutter.

FIG. 6 is a bottom, plan view of the swivel knife holder assembly for a multi-ply reciprocating cutter; and, FIG. 7 is a top, plan view of the swivel knife holder assembly for a multi-ply reciprocating cutter.

1 Claim, 4 Drawing Sheets
